UNITED STATES PATENT OFFICE.

AUGUST F. ZIMMERLING, OF MILWAUKEE, WISCONSIN, ASSIGNOR OF ONE-HALF TO J. A. DUTCHER AND P. E. DUTCHER, OF SAME PLACE.

OIL-STOVE.

SPECIFICATION forming part of Letters Patent No. 369,422, dated September 6, 1887.

Application filed January 17, 1887. Serial No. 224,556. (No model.)

To all whom it may concern:

Be it known that I, AUGUST F. ZIMMERLING, of Milwaukee, in the county of Milwaukee and State of Wisconsin, have invented new and useful Improvements in Oil-Stoves; and I do hereby declare the following to be a full, clear, and exact description of said invention, reference being had to the accompanying drawings, and to the letters or figures of reference 10 marked thereon, which form a part of this specification.

My invention relates to improvements in oil-stoves, and it pertains more especially, first, to the device for raising the chimney, whereby 15 the lamp is inserted and withdrawn therefrom, and, second, to the device for supporting the deflector centrally within and independently of the chimney.

Figure 1 of the drawings represents a front 20 view, part in section, of my improved stove; and Fig. 2 represents a side view thereof, part in section, showing the lamp drawn out in front of the stove and supported by the counter-weight of the reservoir. Fig. 3 is a perspective view, part in section, of the device 25 for holding and adjusting the wick-tube. Fig. 4 represents a top view of the stove, part in section, a top view of the supporting-bracket of the deflector being shown upon the right 30 and a sectional view of the same being shown upon the left, while a top view of one of the lamps is shown drawn forward upon the right, the body or frame being shown in section on a plane slightly above the deflector P.

The body of the stove A resembles in 35 appearance an ordinary stove, and it is provided at its front side with a combustion-chamber, B, and two separate oil-lamps, C, one lamp being located beneath each end of the combustion-chamber. The lamps C are each connected with separate reservoirs, D, by oil-tubes E and the platform F. The reservoirs D are located upon the same plane with the lamps C, with which they are connected, and directly 40 in rear thereof in such manner that as the lamp is drawn forward past the front of the stove the rear end of the platform F and the reservoir D remain within the stove beneath the combustion-chamber and in such position 45 that they counterbalance the weight of and

support the lamp in the position shown in Fig. 2.

To prevent all liability of the lamp C being tipped forward by any accidental pressure thereon when drawn out, the wall of the combustion-chamber extends downward, terminating slightly above the reservoir in such a position as to arrest the upward movement of the reservoir in case the same should be tipped. The reservoirs are each supported on a separate set of stationary rollers, G G. The rollers G are supported upon ordinary bearings, a a, which bearings are supported at the side of the stove by bars H and I.

When the lamps C are in place beneath the 65 chimneys J, the lower end of such chimney overlaps and engages upon and around the upper end of the burner or cone K, thereby forming a close joint between the lamp and the chimney, which is necessary to produce 70 the draft required for combustion.

It is obvious that when the lamp cone and chimney are thus united together it becomes necessary to separate such parts preparatory to withdrawing the lamp from or returning it 75 beneath the combustion-chamber of the stove.

The chimney is disengaged from the cone and elevated preparatory to inserting the cone beneath it by turning the eccentric disks L beneath the chimney-supporting plate M. The 80 plate M is supported at its respective ends on said eccentric, (shown in Fig. 1,) and the chimneys J are supported upon said plate. Thus it is obvious that when the disk L is in the position shown in Fig. 2 the end of the plate M 85 resting thereon is raised and the chimney at such end is thereby disengaged from the cone of the lamp, as stated, when the lamp may be drawn forward from beneath the combustion-chamber. When desirous to move both lamps 90 at the same time, both of said eccentric disks L are raised. The eccentrics L are supported in bearings in the wall of the stove upon pins N N, which project through the wall of the stove, as shown in Fig. 1, and are provided on 95 their exterior ends with a hand-wheel, O, by which they are turned.

The deflector P is supported centrally within the chimney J by the three-armed bracket R, the exterior arms, b, of which are rigidly affixed 100

to the plate M, while the central arm, c, is suspended from the upper end of said bracket centrally above said deflector P, which is attached thereto.

5 The device for adjusting the wick consists of a hollow open cylinder, A', provided upon one side with a vertically-arranged tooth-bar, B', and a small pinion, C', rod D', and hand-wheel E'. The wick is affixed to the exterior 10 surface of the cylinder A', its vertical edges meeting upon the respective sides of said toothed bar B', and when thus secured to the cylinder the wick is caused to move bodily with the cylinder upward and downward as 15 the hand-wheel E' is turned toward the right and left.

I have made a previous application for patent, Serial No. 210,486, which was filed August 9, 1886, which application contains, in 20 part, the same subject-matter as the present application, and I disclaim herein any of the combinations or devices claimed in my said previous application.

Having thus described my invention, what 25 I claim as new, and desire to secure by Letters Patent, is—

1. In an oil-stove, the combination of a movable lamp, C, cone K, affixed thereto and

adapted, when raised, to enter the base of the chimney, supporting-plate M, located above 30 said lamp, chimney J, and deflector P, supported by a bracket affixed to said plate independently of said lamp and chimney, substantially as and for the purpose specified.

2. The combination of the chimney J, chimney-supporting plate M, resting at its respective ends upon the eccentrics L, eccentrics L, and lamps C, said plate M and the chimneys thereon being adapted to be raised and lowered by turning said eccentric and said lamps engaged with or disengaged from said chimneys, substantially as and for the purpose set forth. 35 40

3. In an oil-stove, the combination, with the body A, of the chimney-supporting plate M, located at the bottom of the combustion-chamber, deflector-supporting bracket R, affixed to said plate M, deflector P, affixed to said bracket R above the lamp C within the chimney J, chimney J, and lamp C, substantially as set forth. 45

In testimony whereof I affix my signature in presence of two witnesses.

AUGUST F. ZIMMERLING.
